UNITED STATES PATENT OFFICE.

LOUIS GATHMANN, OF CHICAGO, ILLINOIS, ASSIGNOR TO GEORGE WHITMAN
MCMULLEN, OF PICTON, CANADA.

EXPLOSIVE CHARGE.

SPECIFICATION forming part of Letters Patent No. 726,901, dated May 5, 1903.

Application filed May 27, 1899. Serial No. 718,518. (No specimens.)

To all whom it may concern:
Be it known that I, LOUIS GATHMANN, a citizen of the United States, residing at Chicago, in the State of Illinois, have invented certain new and useful Improvements in Explosive Charges; and I do hereby declare the following to be a full, clear, and exact description of the invention, such as will enable others skilled in the art to which it appertains to make and use the same.

This invention relates to explosive charges for propelling projectiles from guns and similar weapons, and is particularly designed for explosive charges made from colloidal explosive compounds, such as nitrocellulose or gun-cotton alone or combined, and generally of colloidal smokeless explosives, although the same may be applied to other explosives, such as ordinary gunpowder, provided they may be obtained in such a condition as to retain the shapes imparted to them after molding.

The objects of this invention are to obtain a propelling charge which when fired will burn and be consumed at a uniformly-increasing rate throughout its entire mass, and thereby generate gases in a uniformly-increasing quantity, so as to generate a uniformly-increasing accelerating force upon the projectile and to obviate all danger of a sudden undue increase of pressure, which would injuriously affect the gun.

A further object of this invention is to produce a propelling charge whose rate of combustion can be determined with reasonable certainty and accuracy beforehand and which will thus furnish sufficient data to correctly calculate the velocity and trajectory of the projectile to be fired by such charge. As will be readily understood, this is a matter of the utmost importance in gunnery.

It is the object of this invention, moreover, to effect the above results in a manner consistent with cheapness and economy of manufacture.

It has heretofore been proposed to obviate the danger of sudden shocks upon the projectile and the inner walls of the gun or to avoid a decreasing or uneven rate of gas generation by forming smokeless or other powders into sticks or pellets, which were provided with longitudinal perforations. These

perforated pellets or sticks were either introduced into the charge-chamber of the gun in the shape of short sticks or "grains," or a number of long longitudinally-perforated sticks were assembled in the form of cylindrical bundles or fagots held together by a suitable wrapper or envelop of silk, the whole forming a propelling cartridge or bag about the size of the charge-chamber of the gun. Both of these forms of charges are unsatisfactory and will not result in an even burning of the explosive throughout its entire body and in an unimpeded passage of the flames through the perforations or vents in the pellets or sticks, for the reason that if these pellets are made the full length of the charge the generation of gases after ignition proceeds with such rapidity that they cannot escape at the end openings of the cartridge or the charge sufficiently fast to prevent sudden interior pressures or shocks and consequent fracture of the pellets or sticks into numerous small fragments, whereby an enormously-increased surface of the explosive is suddenly presented to the flame, which must necessarily result in an enormous increase of pressure. If the pellets are made shorter than the full length of the charge, their openings or vents cannot in practice be made to register, and hence the occurrence of sudden fracturing-shocks will be enhanced to a still greater extent. In both cases the sudden increase of pressure will not be distributed throughout the entire extent of the chamber, but will generally be very unevenly distributed and largely concentrated at only a portion of the charge-chamber, thus still further increasing the injurious effect of the explosive.

In all known charges the flames cannot come into contact with the exterior of the charge unless the same does not completely fill out the charge-chamber. If the same does not completely fill out the bore of the charge-chamber, its mass will be concentrated at a point below the center of the bore, and hence an unequal pressure will be distributed throughout the same, which of course is objectionable. Furthermore, all the perforated or recessed smokeless-powder charges with which I am acquainted are insufficiently

vented—that is to say, the recesses are so formed and arranged that the gases of explosion generated cannot escape sufficiently fast from the perforations or recesses to prevent their being dammed up, thus fracturing the charge into numerous fragments, and thereby suddenly increasing the combustion-surfaces to a degree which cannot be determined and which will vary for different charges. It is hence impossible to control the pressure or propulsive force obtained from such charges and to accurately calculate the velocity and trajectory of a projectile fired with such powder.

15 My invention has been designed to remedy the above objections and to realize the objects set forth, and a propelling charge or cartridge embodying the said invention is so constructed that it will fill out or substantially fit in 20 the bore of the charge-chamber, while at the same time it permits the practically simultaneous passage of the flames of ignition and combustion to all parts of the charge—to the parts remote from the ignition-point as well 25 as those near the same—the flames passing around the entire outer surface and through the mass of the charge and preferably, also, through the center of the same, the mass of the charge being so arranged, apertured, 30 and recessed that as the combustion proceeds continuously and uniformly increasing surfaces are presented to the action of the flames. Thus there results a uniform and continuous increase in the evolution of propulsive gases 35 and a consequent continual uniform increase of the pressure which urges the projectile toward and out from the muzzle of the gun. Moreover, by my invention the pressure produced by the development of the gases is 40 rapidly and uniformly distributed on the various parts of the charge, so that there will be no tendency to fracture the charge, as would be the case if one portion thereof were submitted to substantially a greater pressure 45 than another.

In the preferable construction of propelling charges embodying this invention the same consists of a central core, from which radiate a series of arms extending the entire 50 length of the chamber, the outer surfaces of said arms forming practically a portion of a cylinder concentric with the inner core. The central core is preferably provided with a central passage for the flames, although in some 55 cases this central passage may be omitted. Between the above longitudinal radial arms are arranged transverse or sectoral spaces which permit the passage of the flames along the entire lateral surfaces of these radial arms 60 of the explosive charge. To further increase the flame-impinged surfaces, these radial arms are honeycombed with numerous transverse passages, which permit the flames to pass through the arms at a sufficiently great 65 number of points, these passages preferably having flaring orifices, so as to obviate any liability of impeded circulation of the flames

and consequent fracture of the charge. It is to be noted, moreover, that these transverse passages are preferably, although not necessarily, of a hexagonal shape, and that the walls of the central passage (in cases where the same is employed) are preferably made parallel to the sides of the hexagonal transverse concentric passages in the radial arms, and that the outer surfaces of said arms are also arranged substantially parallel to the sides of said hexagonal passages. The transverse passages are, moreover, so located with relation to each other and to the outer surfaces of the radial arms and the walls of the central passage of the charge that as the surfaces of the transverse passages are consumed their advancing exposed surfaces meet each other and also the outer advancing combustion-surfaces of the radial arms and in many cases also those of the central opening at intermediate points in such a way that when they meet all of the mass of the radial arms of the charge and all or the greater portion 90 of the central core will have been consumed, thus leaving no residues or only a very small residue of unconsumed explosive of a vastly-decreased surface, thus eliminating the objectionable feature of a sudden decrease in 95 the propulsive acceleration.

A charge having the arrangement and cellular structure above set forth may of course be made in various ways; but it is preferably made from a series of thin disks having 100 the shape of the cross-section of the cartridge and provided with transverse recesses in their radial arms, each recess forming either a portion or the whole of the transverse flame-passages in the radial arms of the cartridge. These star-shaped disks, which may be formed by molding or stamping the explosive in any suitable manner, are assembled or piled one upon the other in a sufficient number to form a complete cartridge, 110 the radial arms of all the disks being preferably in register and the recesses forming the vents or transverse flame-passages in the cartridge. Any suitable cement, adhesive or solvent, of the explosive material of the cartridge which will not interfere with the ready combustion of the explosive and leave objectionable residue may be employed to unite the disks into a single cartridge. 115

In the accompanying drawings I have illustrated a propelling or explosive charge embodying what I consider the best form of carrying out my invention.

In the drawings, Figure 1 represents substantially a full-size face view of one of the star-shaped disks of explosive material forming part of such charge designed for a six-inch gun; Fig. 2, a longitudinal central section along line 2-2, Fig. 1, of a series of such disks piled one upon the other and forming 125 a complete charge or a portion of such complete charge; Fig. 3, an isometric view of a complete charge on a somewhat-reduced scale; Fig. 4, a longitudinal central section 130

of the breech portion of a piece of ordnance with such charge in operative position, also on a reduced scale; Fig. 5, a face view of a disk of explosive material embodying a somewhat-modified form of my invention; Fig. 6, a longitudinal central section of a pair of such disks assembled and united, and Fig. 7 a side elevation of charge under my invention made up of sections; Fig. 8, an isometric view of another modified form of charge under my invention.

Throughout the drawings the same characters of reference designate the same parts.

Referring first to Figs. 1 to 4, it will be noted that the charge or cartridge A is substantially of the form of a cylinder somewhat tapered near its forward portion A' and provided with a series of open longitudinal channels *a*, extending unobstructed its entire length, and also provided with a central channel or bore *b*, also extending unobstructed the entire length of the cartridge. This arrangement of channels is effected by making the charge or cartridge consist of a central longitudinal core B, within which is arranged the central bore *b*, and from which core extend, preferably, radial arms or ribs C, also extending the entire length of the charge and leaving between them substantially triangular or sectoral prismatic and preferably equal longitudinal flame passages or channels *a*, above referred to, whose apexes abut against the core B and which are open at the periphery of the cartridge. These flame-passages extend in the general direction of the length of the unit or charge and are open to the exterior of the same, so that the pressure developed by their respective burning surfaces may be substantially equalized and distributed not only throughout the unit or charge, but also upon the exterior of the same and in the charge-chamber.

The radial arms or ribs C are riddled or honeycombed by series of perforations or vents *d*, which pierce the same transversely at numerous points, as shown, and thereby place the flame-passages in communication with each other, so as to insure the rapid equalization of pressure upon the various parts. The preferable shape and their relative location with respect to each other and periphery of the cartridge, as well as the walls of the central core B, are such that as the charge or cartridge is being consumed their constantly and gradually increasing burning surfaces will meet each other, as well as the advancing surfaces of the peripheries C' of the arms C, along lines where the material of the charge will have been entirely consumed, thus leaving no portion of the material for subsequent combustion on surfaces which suddenly decrease in area, giving rise to sudden pulsations in the pressure or shocks, which would be injurious and which would render it impossible to calculate the propulsive effect of the charge. It is also advisable in many cases to arrange the inner core in such a man-

ner with relation to the vents *d* that the advancing and uniformly-increasing burning surfaces of the central bore will meet the advancing burning surfaces of said vents along lines or surfaces where the material of the charge will be completely consumed, although in some cases it may be desirable to leave a portion of the material near the core unconsumed just as the projectile emerges from the mouth of the gun, the decrease of the acceleration of pressure at this moment being of advantage.

As shown in Figs. 1 and 3, the transverse vents *d* are preferably made flaring from the middle portions *d'* outward, their diameters being greatest at their orifices *d*². This arrangement is for the purpose of avoiding any possible stowing up or accumulation of gases of combustion as they are generated in the vents and of facilitating a perfect escape and circulation of these gases and avoiding fracture of the charge. This form of the vents is desirable in some cases, governed by the particular nature of the explosive employed, the particular construction of the charge, and the gun and projectile employed. In other cases, however, this particular form of vents *d* may be dispensed with.

To effect the uniformly-progressing combustion to the point of complete consumption, many arrangements of the size and configuration and location of the vents *d* and various parts of the charge may be adopted, governed in great measure by the material and disposition of the material employed; but preferably I make the shape in cross-section of the vents *d* and the contour of the walls of the central bore *b* and of the outer periphery of the radial arms or ribs C as follows, particular reference being had to Figs. 2 and 4:

The vents or perforations *d* are of equal regular hexagonal cross-section throughout, and one or a number of substantially parallel vertical rows of such perforations are provided. In the present instance there are three substantially parallel vertical rows of such perforations. These perforations are so arranged that the axis of each perforation of one row lies substantially on a horizontal plane midway between the perforations of the adjacent row or rows. Moreover, the sides of each hexagonal perforation are all substantially parallel to the adjacent sides of the adjacent perforations. Thus, for example, taking the hexagonal perforations 1^d, 2^d, 3^d, and 4^d in Fig. 2, it will be observed that the sides 1^{d2} and 1^{d3} of the inner perforation 1^d are parallel to and equidistant from the sides 2^{d4} and 3^{d4} of the perforations 2^d and 3^d, respectively, also that the sides 2^{d3} and 3^{d2} of the perforations 2^d and 3^d are parallel to each other, while their distance is equal to the distance between the sides 1^{d2} and 2^{d4}, or between the sides 1^{d3} and 3^{d4}, and also that the sides 2^{d4} and 3^{d4} are parallel to and equidistant from the sides 4^{d2} and 4^{d3}, respectively, of the perfora-

tion 4^d, the distance between them being equal to the distance between the sides 4^a and 13^a of the perforations 2^d and 3^d. This arrangement of the perforations extends throughout the mass of the radial arms C, and it results therefrom that if the charge be made of homogeneous material the combustion from the vents d outward will proceed progressively on uniformly-increasing surfaces, which will meet on planes or surfaces midway between the axes of the hexagonal vents, as indicated by the zigzag dotted lines D at the left of Fig. 2 and the horizontal full lines in said figure. It is also desirable that the burning proceeds progressively from the center of the charge outward, so as to meet the advancing surfaces of the charge at a point where the material will all be consumed, and for this purpose I form the central bore b of the charge, as shown in Figs. 2 and 4, with a series of annular triangular corrugations b', which are substantially parallel to the respective opposite portions of the hexagonal perforations d. The surface of the bore is therefore made up of a series of annulets, whose surfaces as they burn outward are progressively and uniformly increased until they meet the opposite advancing surfaces of the inner rows of perforations in the arms C along surfaces indicated by the zigzag dotted line D' at the left of Fig. 2. It is, moreover, advantageous in many cases to so shape the outer peripheries of the radial arms C with triangular corrugations the sides C' of which are substantially parallel to the sides of the adjacent hexagonal perforations d and at such a distance therefrom that their burning surfaces will meet the advancing burning surfaces of the correspondingly-hexagonal perforations along surfaces where the material will have been entirely consumed, these surfaces being indicated by the zigzag dotted line D' at the left of Fig. 2.

The charge shaped and arranged as hereinabove described is preferably manufactured by building the same up from a number of disks or layers E, each layer being an exact duplicate of the other in size, shape, and proportions, as shown in Fig. 2, excepting for the forward end of the charge, where the layers are somewhat reduced in size to fit the reduced diameter of the bore of the charge-chamber of the gun. As shown, each layer E consists of a substantially star-shaped disk having a central annular portion, which forms part of the central core B, and the radial arms forming part of the radial arms or ribs C of the completed charge. On one side of each of the radial arms of each disk E are provided a number of semihexagonal recesses or mortises, in the present case two, while on the reverse side of each radial arm is formed a similar semihexagonal mortise midway between the first mortises.

Of course the number of mortises may be increased or diminished without departing from the present invention. However, un-

der all circumstances they are preferably so formed and arranged that when the layers are assembled the vents d will be arranged as hereinbefore pointed out. The inner core of the disks E is provided with a central perforation, which is to form part of the bore b of the charge, said perforation being annularly beveled, as shown, to form the triangular corrugations b' of the said bore. The outer surfaces of the radial arms are similarly beveled, but in a reverse direction, as shown, so as to produce the corrugated contour of the outer periphery of the radial arms or ribs C, above set forth. These disks are preferably formed by first cutting out star-shaped disks, approximately of the outline shown in Fig. 1, from a sheet of any suitable explosive material in a plastic condition, such as a colloidal nitro compound consisting mainly of gun-cotton or of gun-cotton with other well-known admixtures, which has been rendered gelatinous and plastic by the addition of the proper solvents and kneading or working or in any suitable and well-known manner. The disks thus cut out are then molded or compressed between suitable dies, so as to assume the completed shape shown for the separate disks E in Figs. 1, 2, 3, and 4. The disks or layers E of explosive material so formed are assembled so that two adjoining smaller areas e will alternate with two adjoining larger areas e' of the layers, as will be evident. By this arrangement the triangular corrugated contour of the central bore b and the outer peripheries of the radial arms is produced, and the hexagonal transverse perforations d are completed. The layers E are permanently united into a continuous single charge by first coating their areas e and e' with a suitable adhesive or cement, such as collodion or solvent, which preferably will not interfere with the ready combustion of the explosive material. By this means I obtain a charge or unit consisting of explosive material of uninterrupted continuity, whereby the combustion of the charge and the generation of gases will progress in a regular manner and without any sudden fluctuation. To the base of the charge is secured a suitable priming charge F of any ordinary or suitable quick-burning powder, such as gunpowder, as will be readily understood. As seen in Fig. 3, this priming charge is preferably made of the same outlines as the layers E. The said priming charge F is also secured to the base layer of the cartridge A by any suitable adhesive, cement, or solvent. This priming charge F may also be secured to the forward end of the cartridge or charge or to both the base and the forward end, as shown in Fig. 9.

In some cases it will be desirable for convenience of loading, in the case of great guns and consequent heavy charges, instead of making the charge or cartridge of one piece to make it in two, three, or more units or sections 1, 2, and 3, as indicated in Fig. 7, each

unit or section being composed of a number of united layers E. Each of the sections 1, 2, and 3 will constitute a complete charge alone in those cases where the projectile is to be propelled under reduced pressure, or two of the sections may be employed as a complete charge.

In Fig. 4 I have represented so much of a piece of ordnance of ordinary construction with a charge of explosive material made under my invention in place as is necessary to illustrate the use of said charge. It will be noted from this figure that the charge A practically occupies the entire bore of the charge-chamber g of the gun G, its base substantially resting against the mushroom g' of the breech-block g², so that the fuse or primer, which occupies the vent g³ of the breech-block, will impinge against the priming charge F, forming part of the charge. The forward part of the charge is somewhat tapering in form, as already explained, in order to properly fit into the somewhat-contracted portion g⁴ of the charge-chamber at the base of the projectile H. When the priming charge F is ignited by the primer, the flames therefrom completely envelop the exterior of the charge by passing in an unimpeded current forward through the peripheral channels a. They also pass forward through the bore b, and finally they penetrate every portion of the mass of the charge by passing through the vents or transverse perforations d. The same ready circulation is permitted for the gases of combustion, this circulation being further aided by the corrugated perforations of the radial arms C. The gases of combustion are by virtue of the peculiar construction of the charge evolved with equal rapidity at all points at the bottom as well as at the top and at the forward end as well as at the rear end, and as the burning surfaces are progressively increased the accelerating propulsive force is progressively increased at a substantially uniform rate until the charge has been consumed.

All danger of fracture of the arms is avoided, first, by the fact that each radial arm is supported by two opposite exactly-balanced gas pressures exerted by the gases filling the channels a, and, secondly, by the peculiar shape of the vents d.

In many cases the inner bore b or the outer corrugated periphery of the radial arms, or both, may be dispensed with. The latter construction is illustrated in Figs. 5 and 6, where, it will be noted, the layers E of the charge are represented as composed of solid central cores B, from which radiate the arms or ribs C, as before. In the present instance the transverse perforations d are formed of a series of concentric recesses or mortises of a square cross-section, whose walls are not flaring outwardly, as in the first example. These mortises are in the present instance formed on one side only of each layer E, and the layers are so assembled and united

that the mortised side of each layer will be made to impinge against the unmortised or continuous side of the adjoining layer, as indicated in Fig. 6. The outer peripheries of the radial arms are, moreover, not beveled, so that the peripheries of the completed charge will all form part of the same cylinder. This modified form of charge, 70 while perhaps not as effective in many cases as that first described, enables me to secure all the advantages flowing from the exterior open or peripheral channels or passages a in the first place, and, secondly, from the transverse vents, which in my judgment play also an important part in providing for a free and unimpeded circulation of the gases of ignition and combustion and for a uniform and evenly-distributed progress of the combustion, thus avoiding any danger of sudden increases in pressure or fracture, which might result in the absence of these features. In some cases even the transverse vents d might be omitted, although I consider them important to obtain the best effects.

The outer surfaces of the arms may in some cases be nearer or farther away from the transverse perforations than described in connection with Figs. 1 to 4, and in the former case they may be coated with some composition or coating of slow-burning powder, or they may be compacted, so as to be of denser material.

In Fig. 8 I have represented another modified form of charge formed in layers, which differs from those already described mainly in having the peripheral and longitudinal grooves forming the flame-passages a arranged in helical form, the central bore being omitted. These flame-passages, it will be noted, extend in the general direction of the longer axis of the unit, and hence may be said to be substantially longitudinal. It will be noted, moreover, that said flame-passages are open to the exterior of the unit, so that the pressure developed by their respective burning surfaces may be distributed outwardly as well as through the charge mass. The transverse vents d may be in any suitable or convenient form, such as shown.

The above are some of the many modifications which may be devised under my invention, and it will be readily noted from the above description that a charge or cartridge embodying my said invention is susceptible of many modifications without departing from the gist of the same.

Broadly considered and under one aspect of the invention the same consists in a charge of explosive material composed of a number of united layers of explosive material and under another aspect in a charge or cartridge having exterior or peripheral flame-passages and also in an explosive charge or cartridge 120 having such exterior flame-passages in combination with transverse perforations or vents passing through the mass of the charge, the above features all being preferably combined

to produce the best results. It is to be noted, moreover, that each unit or charge of explosive material made in accordance with my invention is continuous—that is to say, the continuity of the explosive material is uninterrupted—so that there is no danger of sudden fluctuation in the pressure of the gases developed. This continuity, as will be understood from the preceding specification, may be obtained either by making the unit or charge in layers or parts secured into one continuous mass by an adhesive material which will not interrupt the progress of the combustion or by making said unit or charge integral—that is to say, by forming it of one piece direct from the plastic material. I do not, therefore, desire to be confined to the specific details described; but

What I claim, and desire to secure by Letters Patent of the United States, is—

1. A mass or unit of explosive material of uninterrupted continuity in the form of a rod or bar, having a central flame-passage and a plurality of exterior flame-passages, said exterior flame-passages being in communication with each other at a plurality of points.

2. A charge of explosive material consisting of a longitudinal inner core and a series of arms or ribs extending outward from the same, open flame-passages being left between said arms and said arms being provided with transverse passages or vents.

3. A disk of explosive material for a propelling charge consisting of a central core having a central perforation and provided with radiating arms provided with recesses on their upper and lower surfaces, the recesses on the lower surface alternating with those on the upper surface.

4. A disk of explosive material for a propelling charge consisting of a central core having a beveled central perforation and provided with radial arms whose peripheries are beveled oppositely to the central perforation, said arms being provided on their upward surfaces with semihexagonal recesses and with similar recesses on their lower surfaces occupying positions intermediate between the recesses on the upper surfaces.

5. A charge of explosive material composed of a united series of superimposed layers of said material and consisting of an inner core and arms extending outward from the same, said arms being provided with transverse perforations or vents arranged at the planes of union of the layers. 55

6. A charge of explosive material composed of a united series of superimposed layers of said material and consisting of an inner core and arms extending outward from the same, said arms being provided with transverse perforations or vents arranged at the planes of union of the layers, said perforations or vents flaring outwardly from their middle portions.

7. A charge of explosive material composed of a united series of superimposed layers of said material and consisting of an inner core having a longitudinal bore and radial arms extending from said core, said arms being provided with a series of transverse perforations flaring outwardly from their middle portion.

8. A charge of explosive material composed of a united series of superimposed layers and consisting of a central core having a central bore and radial arms extending from said core, said radial arms being provided with hexagonal transverse perforations at the planes of union of the layers arranged at substantially equal distances from each other. 75 80

9. A charge of explosive material composed of a united series of superimposed layers and consisting of a central core having a central bore and radial arms extending from said core, said radial arms being provided with hexagonal transverse perforations at the planes of union of the layers arranged at substantially equal distances from each other, the walls of the central bore and outer periphery of the radial arms being triangularly corrugated so as to be substantially parallel to the sides of the hexagonal perforation. 85 90

In testimony whereof I affix my signature 95
in presence of two witnesses.

LOUIS GATHMANN.
